UNITED STATES PATENT OFFICE.

WILLIAM S. WEBSTER AND GEORGE O. WEBSTER, OF CHICAGO, ILLINOIS.

VENTILATOR.

1,420,002.

Specification of Letters Patent. Patented June 20, 1922.

Application filed July 15, 1921. Serial No. 485,077.

To all whom it may concern:

Be it known that we, WILLIAM S. WEBSTER and GEORGE O. WEBSTER, citizens of the United States, residing at Chicago, in the 5 county of Cook and State of Illinois, have invented new and useful Improvements in Ventilators, of which the following is a specification.

This invention relates to cowls or ventilators which are rotatable so that the outlet always faces away from the direction in which the wind is blowing, thereby improving the draft and facilitating the discharge of smoke from a chimney, or of air 15 from a ventilator stack or flue.

The invention has for its object to provide a very efficient device of the kind stated, and to this end it consists in a novel combination and arrangement of parts to be 20 hereinafter described and claimed.

In order that the invention may be better understood, reference is had to the accompanying drawing forming a part of this specification, and in said drawing—

25 Figure 1 is a side elevation of the device; Fig. 2 is a plan view thereof; Fig. 3 is a central vertical section; Fig. 4 is a front elevation, and Fig. 5 is a rear elevation.

30 Referring specifically to the drawing, 5 denotes a main central drum which is vertically positioned and supported by a rod 6 located centrally within the same, the drum having an anti-friction bearing 7 with the 35 top of the rod so that it may freely rotate, and it is properly centered on said rod by spider arms 8 at the bottom.

From the drum 5 extends a horizontally positioned front flue 9 which opens into the 40 drum and has its outer end also open and extending into an air deflecting and spreading shield 10 supported by the drum by means of straps 11.

Over the drum 5 is mounted a hood 12 45 carrying a vane 13 at the top, and in the top of the drum under the hood is a smoke outlet opening 14.

50 Ordinarily, the wind blowing against the shield 10 is deflected along the sides thereof, whereby it creates a partial vacuum in the flue 9, which results in the smoke being drawn out of the drum 5 through the flue 9, to escape from the outer end thereof into

the shield and from the latter into the external atmosphere, it being understood that the 55 front of the shield is kept facing the wind by the vane 13. When there is little or no wind, the smoke can rise in the drum 5 and pass directly out of the same through the top outlet 14 and the hood 12. 60

The hood 12 extends over the outlet 14 and down along the side of the drum 5, and it is closed at the rear to deflect away from the outlet 14, the smoke escaping from the shield 10. The top of the drum 5 has an upward 65 incline toward the outlet 14, as shown at 5°.

The device will be positioned on top of the chimney so as to bring the drum 5 in alignment therewith, and it is also applicable to ventilator stacks or shafts for facilitating 70 the discharge of air therefrom.

It will be noted in Fig. 2 that the air deflector 10 is flat where it faces the wind and its ends are inclined for a short distance and then extend straight and parallel to the direction the wind is blowing. This arrangement produces a maximum draft, the air being spread laterally and its speed being reduced so as not to cut off or strangle the air or smoke rising in the ventilator and issuing 80 from the flue 9. A conical or pointed deflector with its apex facing in the direction the wind is blowing would produce such a rush of air that its speed would cut off the rising air or smoke in the ventilator. 85

We claim:

1. A ventilator cowl comprising a vertically positioned and rotatably supported drum having a bottom inlet and a top outlet, and also provided with a front outlet flue, a wind deflector and shield over the outer end of the flue, and a hood over the top outlet, said hood having its portion which faces the shield closed.

2. A ventilator cowl comprising a vertically positioned and rotatably supported drum having a bottom inlet and a top outlet, and also provided with a front outlet flue, a wind deflector and shield over the outer end of the flue, and having its wind-facing 95 side flat and the ends thereof inclined, and a hood over the top outlet. 100

In testimony whereof we affix our signatures.

WILLIAM S. WEBSTER.
GEORGE O. WEBSTER.
